SAMUEL WILLIAM TRAYLOR, JR., OF ALLENTOWN, PENNSYLVANIA, ASSIGNOR TO TRAYLOR ENGINEERING & MANUFACTURING COMPANY, OF ALLENTOWN, PENNSYLVANIA, A CORPORATION OF DELAWARE

PRODUCING OIL FROM WELLS AND APPARATUS THEREFOR

Application filed April 25, 1932. Serial No. 607,254.

This invention relates to the taking of oil from wells, and to apparatus therefor. An important object of the invention is to take oil (or other liquid) from a well without incidental waste or excessive consumption of gas, thereby saving valuable gas; increasing the useful life of the well and of the oil field or "dome" from which it draws, and also increasing the total ultimate recovery of oil from the well and from the field; and diminishing the expense of pumping the oil after pumping does become necessary. Other objects and advantages that can be realized through this invention will appear herein-
after.

The essential geological unit of an oil field may be conceived of as a subterranean rock "dome", containing oil-bearing "sands", and also, in its top, natural gas under very high pressure. Beneath the oil there is generally water. When a well is drilled down through the rock dome into the sands, the gas pressure forces the oil up through it, so that it often spouts into the air with tremendous force. The well continues to flow spontaneously only as long as the gas pressure remains high enough to force the oil to the surface: after this, additional oil can only be recovered by artificial means, such as pumping. The ultimate recovery is generally limited by influx of water when the pressure has been sufficiently relieved,—often ruining the well for all practical purposes.

In practice, the serious decline of gas pressure results not mainly from withdrawal of oil through the well, but from blowing off of the gas at the well. The evils of this are well understood in the oil industry, and various governmental efforts have been made to compel oil producers to limit their withdrawals of gas to some reasonable ratio to the oil recovered. However, methods of controlling the gas loss have not proved either efficient or satisfactory.

This invention affords a means of producing or taking oil from a well without loss of any gas except that which is dissolved in the oil. It is applicable equally to flowing wells and to those for which artificial means are employed to raise the oil, such as repressur-

ing with compressed air, or pumping with gas or air, or by any desired type of pump, operated electrically, mechanically, or in any other way. While the use of my invention in a well entails (in itself) no waste or consumption of gas (except that dissolved in the oil) it readily permits of pumping a well with its own gas, as well as of using the gas from one well to pump other wells whose gas pressure may be inadequate.

In the drawing, Fig. I shows a vertical section through an oil well equipped for operation in accordance with my invention, certain portions being broken out and omitted to bring the depth of the well within the limits of the paper.

Fig. II is a simplified diagrammatic vertical section illustrating a modified application of the invention.

In Fig. I, the well is shown with the usual tubular metal lining or casing 4, extending from above the surface of the ground at 5 down to, or into, the oil-bearing sand or stratum 6. As shown, the well extends below the casing 4 into the sands 6. The upper end 75 of the casing 4 is closed or sealed (against direct escape of gas, etc.) by the usual plug 7 screwed into the casing. The plug 7 has a port or elbow passage 8 therethrough, to which is connected a pipe 9: This may serve either to draw off or vent gas from the well (especially if the gas pressure is excessive, or for the introduction of gas (sometimes air) under pressure, if the pressure in the well should be or become too low. The plug 7 also has a port or opening 10 therethrough, to which is connected the inner tube (or delivery conduit) 11 in the well. An extension of the delivery conduit 11 above ground is afforded by a pipe 12 also connected to the plug opening 10. The conduit 11 extends, as shown, down to a point somewhere near the bottom of the well, and its lower portion includes a tube or casing 13 considerably enlarged as compared with the portion above.

The conduit 11 is completely closed at its bottom 14 and for some distance above, but has slots or openings 15 through its vertical wall, preferably at a point within the well casing 4. Inside the conduit 11 is an inner

pipe 16 whose flared upper end joins the outer conduit wall at 17, above the openings 15, and whose open lower end 18 extends down nearly to the closed bottom 14. Gas issuing from the sands 6 cannot enter the lower end of the conduit 11, but bubbles up through the oil around the conduit past the openings 15, and disengages itself at the free surface of the oil in the well, accumulating thereabove. However, oil entering at the openings 15 can flow downward in the conduit 11 around the pipe 16 and then up through the latter quite freely. This construction constitutes a convenient form of trap or "gas anchor" (as it is termed in the art) to prevent gas from entering and ascending in the conduit 11 along with the oil. The conduit 9 is effectively gas-sealed by the entrapped liquid, however, only so long as the liquid level in the well (outside the conduit) remains above the openings 15; for if these openings are once exposed, the gas above the liquid will be entrained with the oil and escape freely through the trap.

In the conduit 11, beyond the gas anchor, there is interposed a valve 20 for controlling the flow through the conduit and thereby regulating the liquid level in the well, always maintaining it above the highest point of entry of oil into the conduit at the openings 15. For opening and closing or shifting the valve 20 for this purpose, any means properly responsive to the liquid level in the well may be employed,—provided it is quite reliable in its action, and provided ample power is afforded for positively moving the valve according to the liquid level. In order to minimize the necessary opening and closing force, I prefer a balanced type of valve 20, such as the double-seated poppet valve shown. Made with equal bevelled heads having very narrow contact zones, such a valve is so closely balanced as to be comparatively easily moved; yet the slight unbalance due to the difference between the pressure-exposed areas of its heads holds it definitely seated until force sufficient to open it properly is brought to bear, and thus obviates wire-drawing. As shown, this valve 20 operates in a chambered and ported structure 21 forming the upper end of the enlarged lower conduit portion 13.

To assure positive operation of the valve 20 at all times, greater force is preferably provided than can be secured from the liquid displacement of floats or other moving parts associated with the valve,—owing to space limitations and the wall thickness of a float required to stand the enormous pressures in many oil wells. By employing liquid-responsive means whose force varies with the height of the liquid in the well, very great valve operating power is directly available; whereas the buoyancy of a float increases but very little after it is once fully sub-

merged. As here shown, a hydrostatic pressure device 22 is used and is located inside the casing 13, where the parts are protected from injury, as well as from violent movements of oil that might affect their action. So located, the hydrostatic device 22 responds perfectly to variations of oil level in the well, even with the conduit portion 13 full of liquid to the exclusion of any gas whatever; whereas a float operating within the casing 13 would require the maintenance there of a constant body of gas (or air) in order to act regularly,—something that it is not easy to assure.

The device 22 consists, preferably, of a (sheet metal) bellows, with its movable top wall 23 attached directly to the stem 24 of the valve 20, and its bottom 25 mounted on an apertured diaphragm or spider 26 suitably mounted in the casing 13, above the openings 15 and the upper end 17 of the inner pipe 16. As shown, the valve 20 is loose on the reduced upper end of the stem 24, between the stem shoulder at 24a and a head-shoulder 24b on the upper end of the stem, so that the stem may have a limited longitudinal movement or play relative to the valve. The valve-opening, bellows-collapsing action of the hydrostatic pressure outside on the device 22 is assisted by a weight 27 mounted on its top 23, around the stem 24. The stem 24 has an extension 28 down inside the bellows, to engage the bellows bottom 25 and thus prevent excessive valve-opening movement. The device 22 is also subject to a valve-closing, bellows-expanding force, so determined as to be always sufficient to close the valve 20 with the liquid level in the well above the tops of the openings 15. In the present instance, this force is a substantially constant fluid pressure inside the bellows 22, whose interior is connected through a passage 29 in the parts 25, 26 with a standpipe 30 extending up (through the structure 21) to a height affording adequate hydrostatic pressure, and preferably open into the well at its top. In operation, the bellows 22 responds to hydrostatic pressure merely, since the gas pressure on the liquid in the well acting outside the bellows is always neutralized or cancelled by the very same gas pressure on liquid in pipe 30 acting inside the bellows.

A resistant but ultimately yielding trigger device 33 may be operatively connected to the stem 24, to hold the valve 20 definitely shut until the device 33 is overcome by substantial rise of the liquid level above that at which the valve closes, and vice-versa. The device 33 here shown is in the nature of a double spring toggle, consisting of helical compression springs each provided with knife-edge end pieces 34, 34 that engage and act on a notched abutment 35 mounted on the lower "skirt" portion of the structure 21 and a lat-

eral notch in the portion 36 of the stem 24. With the valve 20 closed as shown, the springs 33, 33 resist its opening until they come in line on a dead-center; but as soon as 5 this position is passed, they aid the opening force and quickly throw or snap the valve full open. Thereafter, as the liquid level in the well falls, the springs 33 resist the closing force, etc., as before, until the valve 20 10 snaps shut. The longitudinal play of the stem 24 in the valve 20 allows the stem to be moved just past the dead-center of the springs 33, 33, each way, before the stem shoulder 24a or 24b strikes the valve to open 15 or close it.

The use of some such trigger device 33 to secure intermittent opening and closing of the valve 20 prevents "wire-drawing" at the valve, and so makes the valve and its seats 20 last considerably longer. While advanta- 25 geous, however, such a trigger device is not essential to the success of my invention.

In practice oil entering the well from the sands 6 may be forced or drawn up through 25 the conduit 11 by any of the natural or artificial means mentioned above: That is to say, either (in a flowing well) by the natural gas pressure in the well; or by gas (air) under pressure introduced into the well at 8, so as 30 to act on the surface of the liquid around the conduit 11; or by a variety of pumping means, which may be interposed in the conduit 11 at any suitable point or points. In many cases, the natural gas pressure will 35 force the oil up a considerable distance, so that it is only necessary to pump it up the rest of the way. However, the operation and utility of my invention are independent of the particular means employed for raising 40 the oil in the conduit 11; i. e., the invention is useful in any well that produces gas in sub-stantial amounts. Assuming, therefore, merely that adequate pressure or other means of raising the oil is present or provided, a 45 mode of operation is as follows:

Oil from the sands 6 accumulates in the well until it reaches a level such that its hydrostatic pressure on the device 22 (aided by the weight 27) overcomes the closing pressure 50 from the standpipe 30, aided by the springs 33, 33, and carries the springs 33, 33 past dead center; whereupon the valve 20 snaps wide open, allowing a free flow of oil. As this free flow continues, the oil level in the well 55 falls until the head of oil in the standpipe 30 is able to overcome the weight 27 and the resistance of the springs 33, 33, together with the hydrostatic well-pressure on the device 22, when the valve 20 snaps tight shut, completely stopping the oil flow. Accumulation 60 of oil in the well recommences, initiating a repetition of the cycle,—and so on indefinitely. In this cycle of operation, the gas pressure in the well plays no part, since it acts 65 equally on the oil surface in the well and on

the liquid in the open-topped standpipe 30. The effective valve opening force corresponds to the height of the oil above the device 22,—which, as already mentioned, is above the openings 15. The liquid in the standpipe 30 70 will preferably be some of the oil in the well.

The foregoing is the usual mode of operation. There may, however, be an initial period in the life of a well when its gas pressure 75 will suffice to maintain a continuous flow of oil, without any periodic drawing down of the oil level to a point where the valve 20 would close. If at such a time the oil in the well rises above the open top of the stand- 80 pipe 30, this will not affect the subsequent operation as described above later on, after the flow of oil has diminished.

From the foregoing description, it will be seen that by my invention oil can be taken 85 from a well without loss of any gas except that actually dissolved in the oil,—together with any used for pumping the oil, if the gas pressure is insufficient to render the well a "flowing" well. In producing this result, the gas anchor formed by the trapped oil below the openings 15 and the automatic level regulator consisting of valve 20 and level- 90 responsive device 22 have an important co-action; i. e., without the gas anchor, the oil 95 passing the valve 20 would carry quantities of entrained and unseparated gas; while without the level regulator, the oil level in the well would be forced down to the open- 100 ings 15, and the gas anchor emptied of oil and rendered ineffective,—after which large quantities of gas would blow off through the conduit 11, and comparatively little oil. But when maintained effective by the level regu- 105 lator, the gas anchor causes a separation of the gas from the oil, as already described, and permits the oil to be taken off by itself. While gas anchors have heretofore been sometimes used in wells that had to be pumped, they have been found practically 110 useless in flowing wells, for reasons indicated above.

A bellows type of hydrostatic liquid level responsive device 22 can be used under a pressure difference of as high as 100 lbs. per sq. in. for a double-walled sheet metal bellows, thus affording an available force as high as 115 350 lbs. for moving the valve 20 each way. The mechanism shown is almost without friction, and is unaffected by either sand or dry gas. A hydrostatic device 22 will operate perfectly in a sloping well, where a float device could scarcely be made to work at all.

Fig. II illustrates in simplified diagram 120 the use of artificially supplied gas pressure to raise oil in a well equipped with the apparatus of Fig. I, especially on the air-lift principle. Various parts and features here shown diagrammatically may correspond in construction with the showing in Fig. I, and 125 130

are here marked with similar reference characters as a means of dispensing with repetitive description; and it will be understood that accessory features of Fig. I (such as the 5 gas anchor) may in practice be used with the device of Fig. II.

Fig. II shows a reversal of the arrangement shown in Fig. I; i. e., gas (or air) from the supply pipe 9a is introduced through the 10 inner tube or conduit 11a, and oil rises in the well casing 4 around said conduit 11a to the delivery connection 12a, which is here made into the casing 4 instead of to the conduit 11a. Accordingly, the level-responsive device 22 15 controls the admission of gas pressure from the pipe 11a into the bottom of the well to force oil up around the pipe 11a. As shown, the conduit 11a has an annular row of small holes 41a located at an intermediate level between the valve 20 and the subjacent hydrostatic device 22, and below the minimum liquid 20 level at l, so as to allow gas to pass out into the well when the valve 20 is open, and assist in raising the oil on the air-lift principle. When the valve 20 is closed, however, 25 the gas is prevented from escaping, as in Fig. I. Here, again, the device 22 responds to the liquid level in the well, as in Fig. I, always maintaining a level above the point of escape 30 of gas at 41a to mingle with the oil.

Having thus described my invention, I claim:

1. A process or method of taking liquid from a well while preventing the loss of gas, 35 which method comprises opening and closing passage through a delivery conduit for the liquid according to variations of hydrostatic pressure of the liquid in the well, regardless of gas pressure, and thereby always 40 maintaining in the well outside of said conduit, a liquid level above the highest point of entry of liquid into said conduit.

2. A process or method according to the preceding claim, including the further step 45 of maintaining the conduit gas-sealed with entrapped liquid below the lowest point of entry of liquid into the conduit.

3. A process or method of raising liquid from a well on the air-lift principle while 50 preventing the escape of gas, which comprises admitting and cutting off air-lift gas pressure from the delivery conduit according to the variations of hydrostatic pressure of the liquid in the well outside of the conduit, and thereby always maintaining in the well a 55 liquid level above the point of escape of gas to mingle with the liquid in the well.

4. A process or method of raising liquid from a well on the air-lift principle, which 60 comprises admitting and shutting off the air-lift gas according to variations of the liquid level in the well, and thereby always maintaining in the well a liquid level above the point of escape of gas to mingle with the 65 liquid in the well.

5. Apparatus of the character described comprising the combination with an oil well and means for introducing gas under pressure to mingle with the oil and thereby raise it on the air-lift principle, of means controlled by the liquid level in the well for admitting the gas as aforesaid and cutting it off, and thus always maintaining a liquid level above the point of escape of gas to 70 mingle with the oil. 75

6. Apparatus of the character described comprising an inner oil well tube, valve means for controlling passage therethrough, means also controlled by said valve means for introducing gas under pressure to mingle with the oil and thereby raise it on the air-lift principle, and means controlled by the liquid level in the well for opening and closing said valve means and thus always maintaining a liquid level above the point of escape of gas to 80 mingle with the oil. 85

7. Apparatus of the character described comprising an inner oil well tube for supplying gas under pressure to mingle with the oil and thereby raise it on the air-lift principle, valve means controlling the supply of gas, and means controlled by the liquid level in the well for opening and closing said valve means and thus always maintaining a liquid level above the point of escape of gas to 90 mingle with the oil. 95

8. Apparatus of the character described comprising an oil well conduit, valve means controlling flow through said conduit, and means controlled by the liquid in the well for exerting on said valve means opening and closing force substantially exceeding that due to liquid displacement of moving parts operatively associated with the valve, and thus positively moving the valve according to the liquid level in the well, and always maintaining the liquid level above the highest point of entry of liquid into said conduit. 100 105

9. Apparatus of the character described comprising an oil well conduit, valve means controlling flow through said conduit, and means for automatically closing and opening said valve means affected by the liquid level in the well with a valve-opening force proportional to the height of the liquid above a level higher than the highest point of entry of liquid into said conduit, however great such height of the liquid above such level, and thus maintaining in the well a minimum liquid level above such point of entry. 110 115 120

10. Apparatus of the character described comprising an oil well conduit, valve means controlling flow through said conduit, and means responsive to hydrostatic pressure of the liquid in the well, regardless of gas pressure therein, for opening and closing said valve means and thus always maintaining in the well a liquid level above the highest point of entry of liquid into said conduit. 125

11. Apparatus of the character described

comprising an oil well conduit, valve means controlling flow through said conduit, and a pressure-responsive device for opening and closing said valve substantially unaffected by 5 gas pressure, but exposed on its one side to the hydrostatic pressure of the liquid in the well and on its other side to a hydrostatic pressure always sufficient to close the valve with the liquid level in the well above its 10 highest point of entry into said conduit.

12. Apparatus of the character described comprising an oil well conduit, valve means controlling flow through said conduit, a chamber with a pressure-responsive movable 15 wall substantially unaffected by gas pressure, but exposed to the hydrostatic pressure of the liquid in the well and operatively connected to open the valve when collapsed by such pressure, and an open stand-pipe connected 20 to said chamber and extending to a height in the well affording sufficient hydrostatic pressure to expand said wall and close said valve with the liquid level in the well above the highest point of entry of liquid into said 25 conduit.

13. Apparatus of the character described comprising an oil well conduit, valve means controlling flow through said conduit, means controlled by the liquid in the well, regardless 30 of gas pressure, for exerting on said valve means opening and closing force substantially exceeding that due to liquid displacement of moving parts operatively associated with the valve, and trigger means for holding said 35 valve definitely open or shut until said trigger means is overcome by substantial change in the relative opening and closing forces.

14. Apparatus of the character described comprising an oil well conduit, valve means 40 controlling flow through said conduit, means for automatically closing and opening said valve means responsive to the liquid level in the well, and affected thereby with a valve-opening force proportional to the height of the liquid above a level higher than the highest point of entry of liquid into said conduit, however great such height of the liquid above such level, thus maintaining in the well a minimum liquid level above such point of 45 entry, and trigger means for holding said valve definitely shut until said trigger means is overcome by substantial rise of the liquid level, and vice-versa.

15. Apparatus of the character described comprising an oil well conduit, valve means 55 controlling flow through said conduit, and liquid-level-responsive means in said conduit responsive to the liquid level in the well, even with the conduit full of liquid to the exclusion of gas, for opening and closing said valve means and thus maintaining in the well a liquid level above the highest point of entry of liquid into said conduit.

65 16. Apparatus of the character described

comprising an oil well conduit, valve means controlling flow through said conduit, and means in said conduit, below said valve means but above the highest point of entry of liquid into the conduit, for opening and closing said valve means in response to variation in the height of liquid in the well above said responsive means, and thus always maintaining in the well a liquid level above said point of entry.

70 17. Apparatus of the character described comprising an oil well conduit with a gas anchor for preventing entry of gas thereinto, valve means controlling flow through said conduit, and means responsive to the liquid level in the well for opening and closing said valve means and thus maintaining in the well a liquid level above the highest point of entry of liquid into said conduit.

75 18. Apparatus of the character described comprising an oil well conduit with a gas anchor for preventing entry of gas thereinto, valve means controlling flow through said conduit, and means in said conduit responsive, notwithstanding the exclusion of gas therefrom, to the liquid level in the well, for opening and closing said valve means and thus maintaining in the well a liquid level above the highest point of entry of liquid into said conduit.

80 90 19. Apparatus of the character described comprising an oil well conduit with a gas anchor for preventing entry of gas thereinto, valve means controlling flow through said conduit, and means in said conduit responsive to the hydrostatic pressure of the liquid in the well regardless of gas pressure for opening and closing said valve means and thus maintaining in the well outside of the conduit a liquid level above the highest point of entry of liquid into said conduit.

100 In testimony whereof, I have hereunto signed my name at Allentown, Pennsylvania, this 22d day of April, 1932.
